CLAIM

The ornamental design for a towel with attached handle loops, as shown and described.

DESCRIPTION

FIG. 1 is an embodiment of a towel with attached handle loops;

FIG. 2 is a front elevational view of FIG. 1;

FIG. 3 is a right side elevational view of FIG. 1;

FIG. 4 is a top side elevational view of FIG. 1;

FIG. 5 is another embodiment of a towel with attached handle loops;

FIG. 6 is a front elevational view of FIG. 5;

FIG. 7 is a right side elevational view of FIG. 5; and,

FIG. 8 is a top side elevational view of FIG. 5.

The back elevational views of FIG. 1 and FIG. 5 are flat with no surface ornamentation.

The left side elevational view of FIG. 1 is a mirror image of the right side elevational view.

The bottom side elevational view of FIG. 1 is a mirror image of the top side elevational view.

The left side elevational view of FIG. 5 is a mirror image of the right side elevational view.

The bottom side elevational view of FIG. 5 is a mirror image of the top side elevational view.

Stippling indicates texture of an exemplary absorbent fabric, not a visual element applied to the surface of the article.

The evenly spaced broken lines in the drawings depict stitching and form no part of the claimed design.
